UNITED STATES PATENT OFFICE.

CARL J. ANDERSON, OF CHICAGO, ILLINOIS.

MOTOR-STARTING DEVICE.

1,318,345.

Specification of Letters Patent. Patented Oct. 14, 1919.

Application filed June 21, 1916. Serial No. 105,021.

To all whom it may concern:

Be it known that I, CARL J. ANDERSON, a citizen of the United States of America, and a resident of the city of Chicago, county of 5 Cook, and State of Illinois, have invented certain new and useful Improvements in Motor-Starting Devices, of which the following is a specification.

My invention relates to motor starting 10 devices and has for its object improvement in such devices.

In the accompanying drawings—

Figure 1 is a sectional front elevation;

Fig. 2 is a section on line 2—2 of Fig. 1;

15 Fig. 3 is a section on line 3—3 of Fig. 2;

Fig. 4 is a partial view on line 4—4 of Fig. 2; and

Fig. 5 is a detail.

On the slate Z is mounted a frame Y, and 20 in this frame are solenoids consisting of magnets A¹, A², etc., and cores B¹, B², etc. Pivotedally connected to the lower ends of the cores are links C¹, C², etc., and through these 25 links runs a rod L. In link C¹ the hole therein practically fits the rod, but in the other links the holes are slots of varying lengths as shown in Fig. 1. The rod L is the bail of a lever M pivoted at points N on the frame Y. In idle position the lower 30 ends of the links rest on the plate X of frame Y.

Secured to the bottom of plate X is a 35 vacuum dash pot P, the piston of which is connected to the rod L by a connecting rod Q. The action of the dash pot is to restrain the lifting of the rod L, and to return it quickly to its lower position when lifted and released.

Pivoted on the upper part of the frame 40 Y over the magnets A¹, A², etc., are levers D¹, D², etc., which levers support movable carbon contact blocks E¹, E², etc. Secured on the slate Z are brackets R upon which 45 brackets are mounted stationary contact blocks F¹, F², etc., corresponding to the movable contacts. Springs S normally hold levers D¹, D², etc., in the position shown in Fig. 2.

The upper ends of the cores B¹, B², etc., 50 are provided with pins T which are adapted to engage springs V on the under faces of levers D¹, D², etc., and lift said levers so as to bring the movable contacts into electrical connection with the stationary contacts 55 when the solenoids are actuated to raise their cores. The cores and pins T are so

arranged that, in the lower position of the cores, the upper ends of said pins are variable distances from the springs V, as shown in Fig. 1.

The magnets A¹, A², etc., are connected in an electric circuit in such a way that they will all be simultaneously energized upon closing an electrical contact. This circuit is not shown, but may be of any kind which will simultaneously actuate the magnets. The connections to the magnets may be in series or in multiple as is most convenient.

Upon energizing the magnets, the cores begin simultaneously to rise. But as these 70 cores are all connected to the rod L, which in turn is connected to the dash pot, the rise of the cores is gradual and not sudden. Because the pin T on core B¹ is nearer to the lever D¹ than are the pins on the other 75 cores, the lever D¹ will be first moved to bring contact E¹ against contact F¹. When this occurs the core B¹ will be stopped, but this does not stop the upward movement of the other cores because the rod L may 80 move in the long slot in link C¹. Similarly the pin T on core B² will next move lever D² to close E² to F², but the remaining cores may continue to move by reason of the rod L rising in the slot of link C². In the same 85 way the remaining cores close the remaining electrical connections in succession, the operation stopping when the last core closes the last connection.

The object of motor starters is to close 90 electrical connections one by one so as to cut out electrical resistance step by step. The electrical connections having such resistance are well known and need no description. From what has been previously given 95 it will be seen that this device accomplishes this result by closing the movable contacts to the stationary ones in succession. As far as the solenoids themselves are concerned, the closing action would be very quick and 100 nearly simultaneous. The rod L and dash pot P, however, serve as a controlling device to prevent quick action and thereby cause the actual closure to have a definite succession with any desired interval between 105 successive closures. Dash pots may be of any size and are normally provided with adjustable air vents.

What I claim is:

1. The combination with a series of stationary contacts, a corresponding series of movable contacts, and a solenoid and core

for operating each movable contact, said solenoids being so arranged that each core moves a different distance to operate its movable contact, of means for causing said solenoids to operate simultaneously at the same speed so that the movable contacts will be operated successively.

2. The combination with a series of stationary contacts, a corresponding series of movable contacts, and a corresponding series of solenoids so arranged that each solenoid must move its core a different distance to operate its movable contact, of an interconnection arranged to restrain said cores so that their simultaneous operation will be at the same speed, and means for permitting cores with longer movements to continue operation after cores of shorter movement have been stopped.

3. A series of solenoids, a slotted link connected to the core of each solenoid, the slots in the different links being of different lengths, a rod or similar connection extend-

ing through said slots, and a dash pot connected to said rod and serving to control the operations of the solenoids.

4. The combination with a series of contact devices, and a corresponding series of electrical devices for moving the contact devices to contact closing position, each electric device being arranged so that it must move a different distance to operate its contact device, of means by which said electrical devices are started simultaneously and move at the same speed to close said contact devices in succession.

5. The combination with a series of solenoids, and a device for controlling their operations, of means by which the solenoids unitedly and simultaneously operate to move the controlling device, and means by which the solenoids are stopped one by one, the controlling device being moved by the remaining solenoids until the last one is stopped.

CARL J. ANDERSON.
